(57) **CLAIM**

The ornamental design for the hair brush as shown and described.

DESCRIPTION

FIG. 1 is a perspective view of a hair brush showing my new design according to a first embodiment;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a perspective view of a hair brush showing my new design according to a second embodiment;

FIG. 9 is a top plan view thereof;

FIG. 10 is a bottom plan view thereof;

FIG. 11 is a front elevation view thereof;

FIG. 12 is a rear elevation view thereof;

FIG. 13 is a right side elevation view thereof; and,

FIG. 14 is a left side elevation view thereof.

The dashed broken lines in the drawings illustrate portions of the hair brush that form no part of the claimed design.

1 Claim, 12 Drawing Sheets
